STOKER MECHANISM

Harold T. Elum, Glenmont, Ohio, assignor to
Briar Hill Corporation, Millersburg, Ohio, a
corporation of Ohio

Application August 16, 1939, Serial No. 290,515

2 Claims. (Cl. 131—131)

The present invention relates to smoking pipes and is more particularly directed to smoking pipes having an arrangement incorporated therein for controlling the firing of the tobacco and, at the same time, cooling the smoke thus produced, whereby, the heavy oils, tars and moistures are condensed therefrom.

The principal object of the present invention is to provide a stoking unit which can be readily mounted within a smoking pipe bowl and manually operated as desired, to control the firing of the tobacco being consumed, while at the same time, consisting of a minimum number of elements, all of which can be economically produced.

Another important object of the present invention is to provide a smoking pipe having incorporated therein a stoking unit which enables the user thereof to remove all objectionable ingredients from said pipe bowl and also cools the smoke from the consumed tobacco and retains the ingredients condensed therefrom in such a manner that the same may be removed without the necessity of disassembling the stoking unit.

Another and equally important object of the present invention is to provide a smoking pipe stoker unit which can be readily mounted within a smoking pipe of the conventional type for improving upon the character of the smoke produced thereby and which unit can be added to the smoking pipe at a relatively low cost.

Other objects of the invention will be in part obvious and in part pointed out in the accompanying drawing and in the detailed following description based thereupon.

The term "conventional" type as herein used, refers to a smoking pipe having a cylindrical bowl and a stem connected to and extending from the base portion of said bowl.

In the drawing:

Fig. 1 is a side cross sectional detail view of a conventional type of smoking pipe and stoker unit mounted therein:

Fig. 2 is a side elevation of a tobacco supporting plate mounted upon its control rod and which elements are the basic members of the stoker unit according to the present invention.

Fig. 3 is a top view of said tobacco supporting plate showing the centrally located openings formed therethrough.

Fig. 4 is a side elevation of a conventional type of smoking pipe having a modified form of stoker unit mounted therein.

Fig. 5 is a side elevation of the principal elements of the stoker unit disclosed in Fig. 4, which

consists of a tobacco supporting plate and a control rod, and

Fig. 6 is a top elevation of the tobacco supporting plate used with the modified form of stoking unit.

Referring now more particularly to the accompanying drawing wherein like reference characters designate similar parts thereof, numeral 1 refers to a conventional type of smoking pipe having a bowl 2, which bowl has an internal chamber 3 and a stem 4 extending from the base of said bowl 2 with bore 5 thereof in connection with said chamber 3. An opening 6 is formed through the base of bowl 2 and located centrally of said chamber 3 by means of a drill or other convenient procedure.

Referring now especially to the principal form of the present invention as disclosed in Figs. 1 to 3 inclusive of the drawing, there is shown fixedly mounted within said opening 6 a tubular bearing member 7 having an annular flange extending from the upper end portion thereof and which flange 8 is seated upon the lower face of chamber 3, whereby the member 7 is restrained from outward movement through opening 6. Slidably mounted within the bore of bearing member 7 is a tubular control rod 9 having the upper portion 10 thereof formed with a relatively larger outside diameter than the lower portion for contacting the upper face of flange 8 and thereby limiting the downward movement of rod 9 through the bore of member 7. Said enlarged portion 10 of member 9 has a series of openings 11 formed through the wall thereof and opening to within the bore of rod 9. The upper end peripheral portion of rod 9 is threaded as at 12 and the lower or opposite end is also threaded upon its periphery as at 13. Said threaded portion 13 has screwed thereon a cap 14 for closing the lower open end of rod 9.

An annular tobacco supporting plate 15, which extends completely across chamber 3 and slidably contacts the wall thereof, has a tubular projection 16 extending from the central portion of the lower face of said plate, and the interior wall of said projection 16 is threaded for receiving therein in threaded engagement therewith the threaded end 12 of rod 9. Said tobacco plate 15 has a series of openings 17 formed therethrough extending from its upper face to its lower face and centrally positioned in such a manner as to connect the upper face of plate 15 with the bore of rod 9 when said plate is connected thereto.

The foregoing described elements are assembled after opening 6 has been formed through the

- base of bowl 2 by first inserting bearing 7 through the upper portion of opening 6 until flange 8 is seated within chamber 3. By applying an adhesive or cement to the periphery of bearing 7, the 5 same will be fixedly connected to the wall forming said opening 6. Rod 9 is at that time inserted from within chamber 3 through the top end portion of the bore of bearing 7 until portion 10 thereof contacts the upper face of flange 8.
- 10 After rod 9 has been mounted through the bore of bearing 7, cap 14 is screwed upon the threaded portion 13. Plate 15 is slid downwardly within chamber 3 and rod 9 rotated within bearing 7, screwing end portion 12 to within projection 16, 15 whereby plate 15 is connected to said rod 9. The foregoing described method of assembly is merely a suggested procedure, as it is obvious that other steps may be followed equally as well to assemble the unit within the smoking pipe.
- 20 After the assembly of the unit within the pipe bowl 2, tobacco is placed within chamber 3 and seated upon the upper face of plate 15. Upon a flame being applied thereto and the smoker drawing through bore 5, the tobacco will be 25 ignited and the smoke therefrom will pass downwardly through opening 17 to within the bore of rod 9. Said rod 9 is formed of a metallic material having high heat conductivity characteristics such as a lightweight metal, as for example, aluminum or magnesium. The smoke within the bore of rod 9 will be cooled by said rod conducting the heat therefrom to the air surrounding the portion of said rod 9 extending outwardly from bearing 7 beyond the outer surface of bowl 30. 2. The smoke thus cooled will have the moisture, heavy oils and tars thereby condensed therefrom and such condensed ingredients will pass downwardly within the bore of rod 9 and settle upon the interior face of cap 14, which cap 14 can be 35 unscrewed from rod 9 from time to time for removing the condensed ingredients supported thereby. The cooled and dried smoke will pass outwardly from the bore of rod 9 through openings 11 where it will be permitted to expand and 40 thus further cooled in the chamber formed by the plate 15 and the lower portion of chamber 3. The smoke below plate 15 will be gradually drawn therefrom through bore 5 to the smoker, thereby completing the draft from the open end of chamber 3. Various smokers desire the burning portion of their tobacco to be positioned nearer the top of chamber 3 than do others, depending upon the taste of the individual smoker. Therefore, as the tobacco 18 is consumed, the entire body 55 of tobacco 18 is moved upwardly within chamber 3 by pushing rod 9 upwardly through the bore of bearing 7 until the burning portion of the tobacco is positioned as desired, whereupon, rod 9, and consequently plate 15, is lowered from the bottom portion of the tobacco 18, since it has been found that the lower portion of the tobacco will remain relatively drier when the plate 15 is lowered therefrom. Upon complete consumption of the tobacco 18, cap 14 can be removed from 60 the end of rod 9, whereby the condensed liquids are removed from the bore of rod 9 and, at the same time, said rod 9 can be pushed upwardly through bearing 7, whereupon, plate 15 which extends completely across said chamber 3 and 65 thereby contacts the walls of said chamber, is also moved upwardly and removes any ingredients which have formed upon the wall of said chamber 3, whereby the same is cleansed. Plate 15 and rod 9 can then be removed from 70 chamber 3 whereby the entire pipe, as well as 75

the elements of the stoker unit, can be readily cleansed.

Figs. 4 to 6 inclusive, disclose a modified form of the stoker unit as hereinabove described and which unit consists of a rod or tube 20 having a 5 reduced portion 21 which is inserted within an opening of equal diameter formed in the central portion of a tobacco supporting plate 22 and which portion 21 has the head thereof flattened for retaining said plate 22 thereon. Said rod 20 10 is slidably mounted within and through the bore of bearing 7 mounted within an opening 6 formed through the base of the bowl 2 of the conventional type of smoking pipe 1 as hereinbefore described. Said rod 20 is formed from metal and 15 preferably from a metal which readily conducts heat, such as aluminum or magnesium. Said rod 20 and plate 22 are mounted within the pipe 1 by inserting rod 20 end first through chamber 3 and through the bore of bearing 7, whereupon, 20 plate 22 extends laterally of chamber 3 and slidably contacts the wall of said chamber and thereby positions an annular series of openings 23, which are formed therethrough from the upper face thereof to its lower face, adjacent the wall 25 of said chamber.

A smoking pipe having the stoking unit of this modified form incorporated therein is used by inserting tobacco within chamber 3 and upon plate 22, at which time a flame is applied to said 30 tobacco, and the smoker of the pipe, by drawing through bore 5, causes air to be drawn from the open end of chamber 3 to the tobacco and from there through openings 23 to the portion of chamber 3 below said plate 22. The burning portion of the tobacco is positioned relative to the upper end of chamber 3 by pushing rod 20 35 upwardly through bearing 7, thereby advancing plate 22 and the tobacco supported thereon upwardly within chamber 3. As the tobacco is 40 positioned as desired, the plate 22 is drawn away from the lower face of the tobacco in order that said lower face of the tobacco may be maintained relatively dry.

Said openings 23 each being positioned near 45 the wall of chamber 3, will cause the smoke from the burning tobacco to pass downwardly along the walls of chamber 3 and not through the principal body of the tobacco, whereby, the smoke upon contacting said wall will be somewhat 50 cooled and have the moisture, oils and tars condensed therefrom. Upon the smoke passing through openings 23, it will be further cooled upon contacting the heat-conducting rod 20, which rod 20 is maintained relatively cooled due 55 to the air passing around the periphery of the portion thereof extending outwardly of bowl 2. The smoke is thereby further cooled and will have further moisture, heavy oils and tars condensed therefrom before it passes outwardly 60 through bore 5. Rod 20 and plate 22 can be disassembled from the bowl 2 by pushing rod 20 and consequently, plate 22, upwardly through chamber 3, at which time ingredients formed 65 upon the wall of chamber 3 will be removed therefrom by plate 22. Therefore, the pipe 1 and the stoker unit are readily accessible for the complete cleansing thereof.

Both the principal and modified form of stoker 70 unit may be incorporated in new or old pipes of other types than that shown herein and such changes are contemplated by the present invention, however, any modifications to the devices as described and disclosed herein which come 75

within the scope of the appended claims, are deemed to be a part of the present invention.

I claim:

1. A tobacco stoking unit for use in smoking pipes having the stem thereof connected to the lower portion of the bowl, comprising a tube, a bearing member slidably embracing said tube, means closing the lower end of said tube and limiting the upward movement thereof relative 10 to said bearing member, a projection carried by the upper portion of said tube limiting the downward movement thereof relative to said bearing member, openings formed through said tube above said projection, a plate detachably mounted on and closing the upper end of said tube and openings formed through said plate and communicating with the bore of said tube.

2. A tobacco stoking unit for use in smoking pipes having the stem thereof connected to the lower portion of the bowl, comprising a tube formed from a heat-conducting material, a cap detachably connected to and closing one end of 5 said tube, a tubular bearing member having said tube slidably mounted within the bore thereof, an annular flange formed extending from said bearing member, a projection carried by said tube for contacting said flange and limiting the downward movement of said tube, openings formed through said tube at a point above said projection, a plate connected to and closing the other end of said tube and said plate having openings formed therethrough communicating with the 15 bore of said tube.
